UNITED STATES PATENT OFFICE

BENJAMIN W. FREEMAN, OF CINCINNATI, OHIO

HAND GUARD FOR SHOE ORNAMENTING DEVICES

Application filed November 22, 1927. Serial No. 235,100.

My invention relates to guards for shoe ornamenting and perforating devices which will permit the operator of the machine to hold or position work in the machine without danger of having the hands smashed or bruised during the ornamenting or perforating operation.

In the art there has been considerable development of shoe ornamenting machinery in which the shoe to be ornamented is positioned on an anvil type support which permits the shoe part to be fitted or partially assembled prior to the ornamenting operation. In such machines the operator may insert the work in over the anvil type work support, and can either hold or position the work with the hands prior to the operation of the cutting or ornamenting devices with which the machine is equipped. Particularly with such a machine, in which the operator either can or may place the hands into such a position that there is danger of injuring them, it is my object to provide a guard which will reduce the possibility of injury to a minimum.

It is broadly the object of my invention as applied to an anvil type shoe ornamenting device to provide means which will permit portions of the work not to be operated on to be held with the hands with a guard so arranged with relation to the cutting and pressing instrumentalities that injury be prevented.

The above and other objects to which reference will be made during the ensuing disclosure I accomplish by that certain combination and arrangement of parts which I have shown embodied in a cut-out machine having a movable work support.

Referring to the drawings:

Figure 1 is a plan view of the work support of a cut-out machine.

Figure 2 is a front elevation of the work support showing also the presser head.

Figure 3 is a side elevation showing the work support with other component parts of the cut-out machine shown in more detail.

Figure 4 is a front elevation showing a work support with a modified type of guard combined therewith.

Referring first to Figure 3 I have shown the cut-out machine having the anvil 1 and the

presser head 2. The cutting dies are carried on the anvil and a backing web 3 is shown as being movable over the presser head. The anvil shown is slidable in tracks in the base frame of the machine. The carriage 4 for the anvil has flanged rails 5 which fit in channels in the frame of the machine, thereby permitting the work support to be withdrawn to work placing position and then moved into the machine to enable the ornamenting devices to function. The usefulness of my invention, however, is equally important whether the work support be movable or not.

The detachable anvil plate which is elevated from the base is generally indicated at 6, and it may be attached to the carriage by means of a bolt 7 and thumb nut 8 with which the parts may be securely fastened together. Mounted in the upper face of the anvil are the cutting dies 9 with which the work is perforated. Extending flush with the tops of the cutting dies is the stripper plate 10. The stripper plate which in this instance acts as the work support has pins 11 extending down through holes in the anvil and heads 12 on the pins limit their upward movement as induced by springs 13 mounted coaxially with the pins 11 and mounted between the upper face of the anvil and the lower face of the stripper plate.

On the upper face of the stripper plate I have shown the gauge plates 14 which serve to assist in positioning the work for ornamenting. The stripper plate 10 is cut away as shown at 10a to permit the dies to pass through or into the work as caused by the downward pressure of the pressure head or platen.

The stripper plate is provided with extensions 15 having upwardly flared front ends 15a which act as hand guards and present the subject matter of my invention. A convenient location for the hand guard portions is on the stripper plate, although as far as the broad idea is concerned, they might be separate plates attached to the anvil, or they might be otherwise conveniently located. The extensions are spaced from the stripper plate with clearance spaces 16 which provide clearance for the work and portions are bent 100

down at angles of about 45° as indicated at 17 which permit parts of the work not being operated on to be held by the fingers, with the extensions 15 preventing all chance for 5 the operator's hands or fingers being injured during the cutting or ornamenting operation. I have further shown the portions 18 bent down to an angle of approximately 90°. The portions 17 and 18 are preferably inter-spaced as indicated. As far as providing 10 clearance for the work is concerned, the guards only require the downwardly bent portions 17 which may, as shown in Figure 4, be an integral piece, but in order to prevent any chance of the operator extending 15 the fingers up underneath the stripper plate, I have found it preferable to provide spaced tongues, one set bent at such an angle as will allow clearance for the work, and the other bent at such an angle as will prevent the operator 20 extending the fingers up under the stripper plate between the plate and the upper surface of the anvil. The flared front ends 15a of the guards allow the work to be 25 readily positioned. In some instances the flared ends act as guides to assist in the placing of work.

The operation of a cut-out machine 30 equipped with my novel guard plates will be obvious. The work such as is indicated in Figure 1 at 19, is placed over the stripper plate, with portions of the work not to be operated on extending down through the clearance spaces 16. The operator may hold 35 down the work with the hands as is indicated at 20 with the extensions 15 extending above their fingers which will prevent pinching between the presser head and the stripper plate, and with the interspaced tongues 18, if this 40 modification is provided preventing the fingers being pinched between the stripper plate and the upper face of the anvil. It will further be obvious that the bent down portions may all be bent to an angle of about 90° as 45 there is little likelihood of extending the fingers up through the clearance spaces 16.

As far as I am advised the combination 50 of a hand guard with a die unit such as is provided in the die plate 6, dies 9 and stripper plate 10, is broadly new, and as many manufacturers specialize in making die units I claim the combination of a die unit and guard whether or not the die is used for the particular type of shoe ornamenting machine 55 illustrated.

Having thus described my invention, what I claim as new and desire to secure by Letters Patent, is:—

1. In combination with shoe ornamenting 60 instrumentalities so arranged as to provide spaces in which an operator may insert his fingers to hold or adjust work with relation to the ornamenting instrumentalities, guarding means associated with said instrumentalities so arranged with reference to the

space occupied by the operator's fingers when holding work as to block the movement of the operator's fingers into such relation to said instrumentalities as might cause injury, during the ornamenting operation, said ornamenting instrumentalities comprising a support carrying ornamenting means and a stripper plate having a resilient mounting with relation to said dies, and said guarding means comprising extensions of said stripper plate. 70

2. In combination with shoe ornamenting instrumentalities so arranged as to provide spaces in which an operator may insert his fingers to hold or adjust work with relation to the ornamenting instrumentalities, guarding means so arranged with reference to the space occupied by the operator's fingers as to prevent injury thereto, during the ornamenting operation, said ornamenting instrumentalities comprising a support carrying ornamenting means and a stripper plate having a movable relation to said dies, and said guarding means comprising extensions of said stripper plate, said guarding means extending in such position as to block the passage of the fingers of an operator from insertion between said stripper plate and said support. 75

3. In combination with shoe ornamenting instrumentalities so arranged as to provide spaces in which an operator may insert his fingers to hold or adjust work with relation to the ornamenting instrumentalities, guarding means so arranged with reference to the space occupied by the operator's fingers as to prevent injury thereto, during the ornamenting operation, said ornamenting instrumentalities comprising a support, dies mounted thereon, a stripper spaced from said support, and guarding means for blocking the entry of the fingers of an operator between said stripper and support. 80

4. In a shoe ornamenting machine, an anvil type work support, a presser head, said anvil type support comprising ornamenting means, and guarding means so mounted on said support as to block the passage of the fingers into such position as might cause injury during the operation of the presser head, said guarding means comprising extension 100 from said support. 105

5. A unit for use with a shoe ornamenting machine comprising an elevated work support, said support comprising ornamenting dies having a stripper plate spaced from said support, and with guarding means disposed to guard said spacing between said plate and support. 110 115

6. A unit for use with a shoe ornamenting machine comprising an elevated work support, said support comprising ornamenting dies having a stripper plate spaced from said support, and with guarding means disposed to guard said spacing between said plate and 120 125 130

support, said guarding means comprising extensions from said support.

7. A stripper plate for co-action with a cutting die and support therefor being associated therewith and having spaced extensions adapted to act as manual guards.
